UNITED STATES PATENT OFFICE.

CHRISTE JOANNIDES, OF LONDON, ENGLAND.

ARTIFICIAL TEETH AND MEANS FOR FIXING THE SAME.

Application filed December 27, 1920, Serial No. 433,418, and in Great Britain January 13, 1920.

The present invention relates to artificial teeth.

It is the general object of the invention to more securely fasten artificial teeth to 5 their backing.

For a full understanding of the invention, its characteristic features and advantages, reference is made to the accompanying drawings in which

10 Fig. 1 is a sectional view of a tooth embodying the invention;

Fig. 1^a is a rear view thereof, partly in section;

15 Figs. 1^b and 1^c are rear views showing modifications of detail; and

Fig. 1^d is a sectional view showing another form embodying the invention; and

20 Figs. 2-9 are similar views showing various modifications.

Having reference to Fig. 1, *a* represents the usual porcelain body of the tooth and the dotted line *b* indicates the backing of red

25 rubber or of any suitable composition to which the tooth is attached by a pin *c* having

a head *c'* in the backing. The pin is in-

clined to the face of the tooth and is curved in the tooth toward the tip thereof. The

cross-sectional area of the pin is elongated, being longer in the direction of length of

30 the tooth than transversely thereof.

The significance of this construction is as follows:

The greater cross-sectional dimension of the pin in the direction of length of the tooth

35 affords a greater shearing resistance, since the shearing stresses are principally trans-

mitted in the direction of length of the tooth. Secondly, the weakening effect which the

mounting of the pin has upon the body of the

40 tooth is greatly reduced because the reduc-

tion of the dimension of the pin transversely of the tooth correspondingly increases the

strength of the tooth in the direction in which the tooth is naturally weakest. In ad-

45 dition, the angular relation of the pin in-

creases resistance against shearing or break-

ing. In the first instance, the inclined pos-

ition increases the shearing area, but the

principal factor is the partial transmission

50 of the stresses, which normally occur in the

direction of length of the tooth, along the

pin whereby the shearing stress is corre-

spondingly reduced.

As indicated in Figs. 1^a and 1^b, two pins

may be used as was heretofore the practice, 55 or a single pin may be applied, as indicated in Fig. 1^c.

There is a great deal of latitude as to the specific details. Above all, the pin portion outside the tooth or in the backing may have 60 any desired form. In practice I prefer to make it as sturdy as possible. There is no restriction whatever in this respect. The pin thus may be round or angular in the backing.

While the concurrence of the various features as described in connection with Fig. 1 is instrumental in producing a particularly good construction, the several features may be separately incorporated. Thus, as indicated in Fig. 1^a, the pin is not inclined, but enters the tooth substantially at right angle, as was heretofore the practice. However, the flattened portion within the tooth, as described in connection with Fig. 1, increases 70 the strength of the tooth. On the other hand, the inclination of a round pin, as for instance indicated in Figs. 8 and 9, increases the strength of the connection as explained.

In practice I prefer, of course, the concurrent application of the two features to derive a maximum of resistance of tooth and connection.

In the arrangement as shown in Fig. 4, the pin lies level or horizontal, is flat inside the tooth, and tapers down in width towards its head *C*, the part outside the tooth being round in cross section as in Figs. 1 to 3.

As is particularly apparent from Fig. 7, the portion of the pin inside the tooth may 90 be disposed horizontally, while the portion in the backing may be inclined to the tooth.

The anchoring of the pin in the tooth may be effected in various ways. As indicated in Figs. 1 and 5, the pin may be curved to 95 safely secure it. In the form shown in Fig. 9 no special means are provided. Due to the inclination the pin extends a greater distance into the tooth and the angular position affords an anchoring effect. However, a head may be provided in various ways, as indicated in various figures.

In practice I prefer to have the head *c'* in the backing inclined or disposed in a plane approaching parallelism to the exposed surface of the backing, as indicated particularly in Figs. 1, 2, 3, 4, 5 and 8.

In the foregoing I have described the es-

sential features of the invention as they may be incorporated separately or together in various forms.

I claim:

- 5 An artificial tooth having a rigid pin for attachment to a backing, the portion of the pin within the tooth being elongated in cross-section in the direction of the length of the tooth, and the portion of the pin ex-

terior of the tooth merging gradually from 10 said elongated section to a circular cross-section, the two said portions being substantially in axial alignment, the portion of the pin exterior to said tooth terminating in an enlarged head, the axis of which is inclined to 15 the axis of the tooth.

In testimony whereof I affix my signature.

CHRISTE JOANNIDES.
